UNITED STATES PATENT OFFICE.

RUSSELL B. BENNETT, OF WESTERVILLE, OHIO.

FENCE-POST.

SPECIFICATION forming part of Letters Patent No. 773,706, dated November 1, 1904.

Application filed August 10, 1904. Serial No. 220,290. (No model.)

To all whom it may concern:

Be it known that I, RUSSELL B. BENNETT, a citizen of the United States, residing at Westerville, in the county of Franklin and State of Ohio, have invented certain new and useful Improvements in Fence-Posts, of which the following is a specification.

This invention belongs to the type of posts which are indestructible and comprise a body 10 formed of cement or like material and a core or filler of metal for strengthening the post and maintaining it in serviceable condition even though the body portion should become broken or cracked.

15 The purpose of the invention is to devise a post of the character aforesaid which may be used in the construction of fences or in the stringing of telephone or telegraph wires or wherever a pole or support of kindred nature 20 may be required.

In accordance with this invention the core or stiffener comprises a member and a plurality of ties strung upon said member, the parts being wholly embedded in the material 25 comprising the body of the post.

The invention further contemplates a post of the character described having offstanding lugs to form a support for the runner elements of fencing, such as rails or longitudinal wires; also in tie-wires molded into the 30 post and extended obliquely therethrough, whereby the opposite end portions of a tie-wire lie in different planes and are adapted to be engaged with proximal runner-wires.

35 The invention also contemplates, in combination with the post, links embedded therein and having their end portions projected beyond opposite sides of the post to receive binder-wires employed for attaching the fence-wires to the posts, said links being preferably disposed in an oblique direction to receive opposite portions of a binder in different planes.

40 A further purpose of the invention is the provision of a core of skeleton formation, the same comprising a plurality of spaced elements, such as wires or rods, and ties for connecting said members to hold them in determinate relation.

45 For a full description of the invention and 50 the merits thereof and also to acquire a knowl-

edge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a side view of a fence-post embodying the invention, showing fence-rails and a fence-wire connected thereto by different securing means. Fig. 2 is a front view of a fence-post embodying the invention, a portion being broken away to show the relation 60 of the core and ties and illustrating a series of fence-wires and the manner of connecting them to the post. Fig. 3 is a rear view of a fence-post constructed in accordance with this invention, showing the end portions of the 65 tie-wires extended. Fig. 4 is a view in section of a modified form of fence-post. Fig. 5 is a sectional view of a further modification, showing the core comprising a central support composed of sections and showing the 70 upper end portions of the core elements extended to serve as securing means for barbed or other wires applied to the upper portion of the post. Fig. 6 is a front view of a fence-post, showing differently-constructed core 75 and opening near the upper end for the reception of a pipe or rod. Fig. 7 is a transverse section of the post on the line *a a* of Fig. 4, showing the parts on a larger scale. Fig. 8 is an enlarged section on the line *c c* of Fig. 85 4, showing the end portions of the tie wrapped about a fence-wire. Fig. 9 is an enlarged section on the line *b b* of Fig. 4. Fig. 10 is a detail view of a fragmentary portion of a fence-post, showing oppositely-disposed 90 L-shaped lugs. Fig. 11 is a plan view of a plate forming a tie for the core elements and having a plurality of openings. Fig. 12 is a plan view of a modified form of tie or connector. Fig. 13 is a sectional detail view of 95 a modified form of post.

Corresponding and like parts are referred to in the following description and indicated in all the views of the drawings by the same reference characters.

The post may be of any size or construction, dependent upon its particular use and location. As illustrated, the post is of trapezoidal form in cross-section, the longer side 5 of the figure constituting the face. This form is preferred, as the greatest length of the post in cross-section is in line with the fence and best adapted to withstand the strain. It is also preferred to have the post slightly 10 tapered throughout its length, although this is not essential. The foot of the post is provided with oppositely-disposed lugs 1, which sustain the post and prevent its withdrawal or upheaval by reason of the earth tamped 15 upon said lugs. In some forms of the post lugs 2 are projected therefrom at intervals in its length to form supports for the fence-rails or other elements. These lugs, as shown in Fig. 1, are of tapering form and are squared 20 upon their upper faces to form seats for the fence-rails 3. As shown in Fig. 10, the lugs 4 are of L form and are oppositely disposed, so as to receive a fence-rail or a wooden strip 3^a when placed in position and prevent both 25 from vertical and lateral displacement. Openings 5 are formed in the members of the lugs 4 to receive nails or like fastenings for securing the rail against longitudinal movement after being placed in position. A series of 30 grooves 6 are formed at intervals in the rear side of the post and constitute seats to receive the fence-wires and prevent their vertical displacement when properly positioned and secured.

35 The core may consist of a single element 7, as shown in Fig. 2, or a plurality of elements or members bound together, as indicated in Figs. 4, 5, and 6. The core may be formed of wire or consist of a rod or bar. A series 40 of plates 8 are strung upon the core, and in the event of a number of elements being embodied in the formation of a core said plates serve as ties for uniting the same at intervals, thereby resulting in the provision of a substantial structure. When the core consists 45 of a single element or member, as indicated in Fig. 2, the plates 8 serve to fix its position and to materially strengthen the post as a structure. In the preferred construction a 50 plurality of elements or members are utilized in the formation of the core. These members are passed through openings 9 in the plates 8 and may occupy any determinate position. The plates may be of a uniform size, 55 as indicated in Figs. 2, 4, and 5, or different-sized plates may be employed, as indicated in Fig. 6. In the latter instance intermediate core elements or members are cut to admit of the formation of an opening 10 in the post at 60 any determinate point for the reception of a rod, bar, or pipe. It is to be understood that any number of openings 10 may be provided, according to the number of rods or pipes to be supported longitudinally in the posts.

65 As indicated in Fig. 5, the core elements or

members are intertwined or otherwise connected near their upper ends and are extended through the post, as indicated at 11 and 12. The side extensions 11 admit of connecting a barbed or other fence-wire to the side 70 of the post near its upper end. The vertical extensions 12 provide convenient means for securing a barbed or other fence-wire to the top of the post. Instead of having the extensions form integral parts of the core elements they may be short lengths of wire molded in the upper portion of the posts, as indicated at 13 in Fig. 4, the lower ends of the wires 13 being bent or otherwise formed so as to obtain firm anchorage within the post. 80

The preferred means for connecting the fence-wires 14 to the posts consists of short binding-wires 15, which are embedded in the posts during the process of manufacture. The binding-wires 15 are preferably arranged in 85 an oblique direction, the inclination being such as to admit of opposite end portions of a binder engaging with adjacent or proximal fence-wires, as indicated most clearly in Fig. 2. The topmost and the lowest binding-wires 90 15 are disposed at a slight inclination to admit of their opposite end portions being wrapped about the same fence-wire, as indicated most clearly in Fig. 2. The binding-wires 15 are located about central of the post, 95 and their end portions project beyond opposite edges. These binding-wires may be utilized during the process of molding the posts to serve as supports for the core and prevent its sinking or settling during the setting process of the cement or other plastic composition. In some instances links 16 are molded into the posts and their members cross so as to embrace the core members, as indicated most 100 clearly in Figs. 9 and 4. The end portions 105 of the links project beyond opposite sides of the post to receive binding-wires separate and independent of the post when employed for attaching fence wires, rails, or the like to the posts, as indicated near the bottom of 110 Fig. 1.

Within the purview of the invention the elements comprising a core may be united by any means other than plates 8. As shown in Fig. 12, a metal trip or blank is bent into rectangular formation and is provided at the corners with eyes 17, through which the core elements are passed. This form of tie is designed to be used in substantially the same manner as the plates 8.

Fig. 13 indicates a fragmentary portion of a post embodying the invention, the core consisting of a coil 18 of wire, the volutes being spaced apart and receiving the cement or plastic composition between them, so as to insure the formation of a substantial structure.

Fig. 1 illustrates one manner of connecting a fence-wire 14 to the post, the binding-wire 19 being bent to embrace opposite sides and the rear of the post and having portions fitted

in adjacent grooves, the binder in side elevation being of V form. Fig. 1 also shows fence-rails 3 attached to the post by means of a clamp 20 and a binder 21. The clamp 20 is 5 adapted to embrace three sides of the post and to have its closed end enter a groove 6. The fence-rail shown near the bottom of Fig. 1 is attached thereto by means of the binder-wire 21, which has an arrangement somewhat 10 similar to the binder-wire 19, with the exception that its side portions extend through opposite ends of the link 16.

In constructing a post in accordance with this invention the body portion is formed of 15 cement or other plastic composition which may be readily worked and molded, so as to completely fill all the space between the component parts of the core and which is self-setting and is not affected by dampness or the 20 elements. The core is formed as an article and is subsequently placed in a mold or form into which the cement or post-forming mold is filled and tamped and troweled or struck, so as to present a smooth side.

25 In the construction shown in Fig. 5 the core comprises a centrally-disposed member 22, which is composed of a series of sections, which sections being passed through openings of certain plates and having their extremities 30 abutted against the certain other plates, this sectional core element serves to place the post longitudinally. While it is preferred to have the core occupy a central position, this is not essential within the scope of the invention, as the core may be arranged to one side of the center nearer any one face of the post.

35 Having thus described the invention, what is claimed as new is—

1. A post comprising a body portion of 40 plastic material, and a metallic core embedded in said material and composed of a series of members, the end portions of which are inter-twisted and extended beyond the post to serve as connecting means for a fence-wire, sub- 45 stantially as specified.

2. A post having its body portion composed of plastic material, a core embedded in the post, and a series of binding-wires embedded in the post and having a transverse oblique arrangement and their end portions projected from opposite sides thereof at different points, and adapted to be engaged with adjacent fence-wires, substantially as set forth.

50 3. A fence-post comprising a body of plastic material, a metallic core composed of longitudinal members transversely spaced and secured together and embedded in the plastic material, and tie-wires passed obliquely

through the post and between the core members and having their end portions extended 60 beyond opposite sides of the post at different points, substantially as and for the purpose specified.

4. A concrete post with a metallic core composed of longitudinal members transversely 65 secured in relative position by perforated core-plates before being embedded in the plastic material and embedded in the central portion thereof, the interspaces being completely filled with the plastic material, with lugs at the bottom of the post on the sides adjacent to the face, with perforated horizontal lugs across one side of the post having upward or downward projecting L's substantially as described.

5. A concrete post of a trapezoidal section 75 with a metallic core composed of members running longitudinally and transversely secured in relative position by perforated core-plates, the members being passed through said plates before being embedded in plastic material, 80 and shaped closely against the lower core-plate and twisted against the upper core-plate, the middle member being in sections passing through the center perforations of certain plates and fitting closely against the other core-plates, not perforated at the center, and the completed core embedded in the post, the interspaces being completely filled with the plastic material, with the free upper ends passing out the sides or the top of the post to receive the 85 top fence-wire or barbed wires.

6. A concrete post with a metallic core composed of a number of longitudinal members transversely secured together by perforated core-plates before being embedded in the plastic 95 material and embedded in the central portion of the post, the interspaces being completely filled by the plastic material, with a perforation near the top of the post between core-plates and sections of the members for the purpose specified.

7. A concrete post of a general trapezoidal section with a metallic core composed of a single longitudinal member passed through the center perforations of transverse perforated 105 core-plates before being embedded in the plastic material, and wholly embedded in the post with the perforations and the spaces between the core-plates being completely filled with plastic material.

110 In testimony whereof I affix my signature in presence of two witnesses.
